(57) **CLAIM**

The ornamental design for an extrusion T-joint connector and cover assembly, as shown and described.

DESCRIPTION

FIG. 1 is an upper front perspective view of the connector of the extrusion T-joint connector and cover assembly of the present design;

FIG. 2 is a lower rear perspective view of the connector of the extrusion T-joint connector and cover assembly of the design of FIG. 1;

FIG. 3 is a top view of the connector of the extrusion T-joint connector and cover assembly of the design of FIG. 1;

FIG. 4 is a bottom view of the connector of the extrusion T-joint connector and cover assembly of the design of FIG. 1;

FIG. 5 is a front view of the connector of the extrusion T-joint connector and cover assembly of the design of FIG. 1;

FIG. 6 is a rear view of the connector of the extrusion T-joint connector and cover assembly of the design of FIG. 1;

(Continued)

FIG. 7 is a side view of the connector of the extrusion T-joint connector and cover assembly of the design of FIG. 1; FIG. 8 is an upper front perspective view of the cover of the extrusion T-joint connector and cover assembly of the present design;

FIG. 9 is a lower rear perspective view of the cover of the extrusion T-joint connector and cover assembly of the design of FIGS. 1 and 8;

FIG. 10 is a top view of the cover of the extrusion T-joint connector and cover assembly of the design of FIGS. 1 and 8;

FIG. 11 is a bottom view of the cover of the extrusion T-joint connector and cover assembly of the design of FIGS. 1 and 8;

FIG. 12 is a front view of the cover of the extrusion T-joint connector and cover assembly of the design of FIGS. 1 and 8;

FIG. 13 is a rear view of the cover of the extrusion T-joint connector and cover assembly of the design of FIGS. 1 and 8;

FIG. 14 is a side view of the cover of the extrusion T-joint connector and cover assembly of the design of FIGS. 1 and 8;

FIG. 15 is an upper front perspective view of the assembly of the extrusion T-joint connector and cover assembly of the design of FIGS. 1 and 8;

FIG. 16 is a top view of the assembly of the extrusion T-joint connector and cover assembly of the design of FIGS. 1 and 8;

FIG. 17 is a bottom view of the assembly of the extrusion T-joint connector and cover assembly of the design of FIGS. 1 and 8;

FIG. 18 is a front view of the assembly of the extrusion T-joint connector and cover assembly of the design of FIGS. 1 and 8;

FIG. 19 is a rear view of the assembly of the extrusion T-joint connector and cover assembly of the design of FIGS. 1 and 8;

FIG. 20 is a side view of the assembly of the extrusion T-joint connector and cover assembly of the design of FIGS. 1 and 8; and,

FIG. 21 is a perspective view of the connector of the design of FIG. 1 and the cover of the design of FIG. 8, in the environment of use, of the extrusion T-joint connector and cover assembly of the present design.

In the drawing, the broken lines show the environment of use of the extrusion T-joint connector and cover assembly and do not form a portion of the design claim.
